UNITED STATES PATENT OFFICE

HENRY F. STOCK, OF WAUKESHA, WISCONSIN, ASSIGNOR TO MICHAEL YUNDT COMPANY, OF MILWAUKEE, WISCONSIN, A CORPORATION OF WISCONSIN

BOTTLE-CLEANING APPARATUS

Application filed November 15, 1922. Serial No. 601,043.

This invention relates to bottle cleaning apparatus, and the object of the invention is to improve the construction and operation of bottle cleaning apparatus in the manner to be hereinafter described and claimed.

Referring to the drawings which accompany this specification and form a part hereof, which drawings illustrate an embodiment of this invention, and on which drawings the same reference characters are used to designate the same parts wherever they may appear in each of the several views, Fig. 1 is an elevation of one side of the bottle cleaning apparatus, parts being broken away and some parts being omitted for clearness of illustration; Fig. 2 is an elevation of the other side of the apparatus; Fig. 3 is a plan view of parts of the apparatus drawn to a larger scale, parts being broken away; Fig. 4 is a section taken on the line 4—4 on Fig. 5, looking in the direction indicated by the arrows; Fig. 5 is a section taken on the line 5—5 on Fig. 4, looking in the direction indicated by the arrows; Fig. 6 is a section taken on the line 6—6 on Fig. 3, looking in the direction indicated by the arrows; Fig. 7 is a section taken on the line 7—7 on Fig. 6, looking in the direction indicated by the arrows; Fig. 8 is a section taken on the line 8—8 on Fig. 9, looking in the direction indicated by the arrows; Fig. 9 is a section taken on the line 9—9 on Fig. 8, looking in the direction indicated by the arrows; Fig. 10 is a section taken on the line 10—10 on Fig. 3, looking in the direction indicated by the arrows; Figure 11 is a fragmentary detail view illustrating the kicker mechanism for the covers employed at the discharge end of the water tank; and

Figure 12 is a similar view partly in plan and partly in horizontal section.

Referring to the drawings, the reference numeral 1 designates a soaking tank which can be of any suitable construction. The endless sprocket chains 2 and 3 pass around sprocket wheels 4, 5, 6 and 7, and 8, 9, 10 and 11, respectively, and these sprocket wheels are secured in pairs upon shafts 12, 13, 14 and 15. The shaft 13 is illustrated as supported in movable journal boxes which can be posi-

tioned by screws 16 and 17. Bottle receptacles 18 are connected to the chains 2 and 3, and are preferably provided with a plurality of compartments 19, one compartment for each bottle, and each bottle receptacle 18 is provided with a cover 20. The covers 20 are provided with notches 21 in their free edges, a notch being provided for each compartment, and the covers are hinged to the bottle receptacles by hinges 22 in a well-known manner. The covers 20 are provided with laterally projecting pins 23 and 24 which contact with cams and guides to close the covers and keep the covers closed to prevent bottles from floating out of the compartments 19 as the bottles are carried down, bottoms foremost, into the cleansing solution in the soaking tank 1, and to prevent bottles from falling out of the compartments 19, prior to their reaching the discharging position, as the bottles are being carried up out of the cleansing solution with their necks down.

The bottle receptacles 18 are secured to the chains 2 and 3 in inclined positions with respect to the travel of the chains so that bottles therein can slide out by gravity at the discharge end of the soaking tank 1 when the bottle receptacles have arrived at the discharging position.

The drawings illustrate an electric motor 25 as a power device to drive or rotate the loose pulley 26 on the shaft 27, and the drawings illustrate ordinary speed-reducing and belt-transmission mechanism to transmit power from the electric motor 25 to the loose pulley 26. A clutch 28 serves to clutch the loose pulley 26 to the shaft 27, to rotate the shaft 27, or to unclutch the loose pulley 26 from the shaft 27, to prevent the rotation of the shaft 27 by the electric motor 25. The clutch 28 can be of any suitable construction, and the drawings illustrate a common type of clutch comprising a clutch member 29 on the loose pulley 26 and a clutch member 30 splined (the spline not shown) to the shaft 27 and movable to clutching position by compressed air acting upon a piston 31 in a cylinder 32. A spring 33, which is interposed between the piston 31 and the cylinder-head 34, moves

90

95

100

the parts to unclutched positions when the pressure of the compressed air is reduced sufficiently in the cylinder 32. A pipe 35 supplies compressed air from any suitable source of supply to the cylinder 32, and valves 36, 37 and 38 are provided in the pipe 35 for shutting off the compressed air from the cylinder 32 and permitting the compressed air to exhaust from the cylinder 31 so that the spring 33 can force the piston 31 back and unclutch the loose pulley 26 from the shaft 27. The piston 31 and the cylinder 32 constitute a simple form of fluid-pressure motor for utilizing a fluid under pressure, and may be considered as a conventional illustration of a well-known type of motor. Each of the valves 36, 37 and 38 is illustrated as an ordinary three-way valve, the valve plugs being provided with straight bores therethrough and each valve plug being provided with an additional bore communicating with the straight bore. Each valve body is provided with an exhaust port, and when the valve plug is turned to one position the exhaust port is closed and compressed air can pass through the straight bore and the pipe 35 to the cylinder 32, but when the valve plug is turned to its other position communication between parts of the pipe 35 on opposite sides of the valve is interrupted, and the cylinder 32 is opened to exhaust.

The shaft 27 is provided with the worm 39 which meshes with the worm wheel 40 which is fast on the shaft 12, and it will be readily understood that when the clutch 28 is clutching the pulley 26 to the shaft 27, and the electric motor 25 is rotating the pulley 26 and the shaft 27, the sprocket wheels 4 and 8 will be rotating and moving the endless chains 2 and 3 in the direction indicated by the arrows to carry the filled bottle receptacles down into the cleansing fluid in the soaking tank 1 and up to their discharging positions, where the bottles are discharged, and to carry the emptied bottle receptacles back to their filling position for refilling with bottles to be cleaned.

The filling end of the soaking tank 1 is designated by the reference numeral 41, and the discharging end by the reference numeral 42.

When the bottle receptacles 18 are passing their filling position their covers will be open, as clearly shown by Figs. 4 and 5 of the drawings, and an operator will place a bottle in each compartment. The bottle receptacles are constructed for bottles of a certain size, bottles of different sizes being ordinarily cleaned on different machines adapted to the size of bottles to be cleaned, and there are two primary causes of trouble which may result in damage to the apparatus. The covers 20 are intended to close over the shoulders of bottles with the necks of the bottles project-

ing through the notches 21. If too large a bottle be inserted in a compartment, a cover 20 will contact with the shoulder of the bottle and be prevented from being closed properly. If too small a bottle be inserted in a compartment the bottle neck might not be centered in registration with the cover notch 21 so that the cover may catch on the end of the neck of the bottle and be prevented from being closed properly. If a broken bottle, though of proper size when unbroken, be inserted in a compartment, it may be long enough for the cover to catch upon it the same as if it were an undersized bottle. In order to prevent damage to the apparatus, means are provided to stop the movements of movable parts of the apparatus unless the covers 20 can be properly closed. The reference numeral 43 designates a guide which is affixed adjacent one side of the soaking tank 1 for the pins 23 to 35 track on to keep the covers 20 closed, and the, reference numeral 44 designates a similar guide fixed adjacent the opposite side of the soaking tank for the pins 24 to track on to keep the covers 20 closed. With pins on the ends of the covers, the covers can be made lighter than if a single pin at one end were relied upon to close a cover and keep the cover closed. Above the extremities of the guides 43 and 44, at the filling end of the soaking tank, cams 45 and 46 are mounted upon spindles 47 and 48 and are properly shaped so that, when the bottle receptacles 18 are moved past them, the pins 23 and 24 will contact with their respective cams and move the covers 20 to closed positions prior to the passage of the pins 23 and 24 into contact with the guides 43 and 44. If a cover 20 is prevented from being properly closed, the cams 45 and 46 will be turned, turning the spindles 47 and 48, and stop the movements of the movable parts of the apparatus in the following manner. A crank 49 is secured to the spindle 47 and is connected by a connecting rod 50 with a crank 51 which is secured to a shaft 52 extending through the soaking tank 1 and which has another crank 53 secured thereto. The crank 53 is connected by a connecting rod 54 with a crank 55 which is secured to the spindle 48. The crank 55 has a crank-arm 56 from which is hung a weight 57 for holding the cams 45 and 46 in their normal positions with sufficient resistance to movement to normally close the covers 20 as the pins 23 and 24 are moved over these cams. A stop 58 can be placed in any convenient position to determine and limit the downward movement of the weight 57 to properly position the cams 45 and 46. The crank 55 is also provided with a crank-arm 59 to which is pivoted a hook 60 which projects over the handle 61 of the valve 36. A pivoted, counterbalanced bent-lever 62 is also pivoted to the hook 60 to compel the upper end of the hook to move substantially to the arc of a circle, this result being accom-

plished by having the pivot 63 set below and back of the spindle 48 and the crank-arms 59 and 64 non-parallel, as clearly shown by Fig. 5 of the drawings.

It will be evident that, if a cover 20 be prevented from being closed properly, the pins 23 and 24 will rock the cams 45 and 46 and pull the hook 60 down and turn the valve handle 61 to shut off the flow of compressed air through the pipe 35 to the cylinder 32, and to permit the compressed air to exhaust from the cylinder 32 through the valve passages 65 and 66 in the valve-plug and through the exhaust port 67 in the valve-body. The spring 33 will then disengage the clutch 28 and permit the pulley 26 to rotate without rotating the shaft 27, and the movable parts of the apparatus will stop.

The guides 43 and 44 terminate short of the discharge point for the bottles from the soaking tank 1, and a kicker 68 is provided to positively open the covers 20. The kicker 68 is illustrated by the drawings as a crank-arm on a shaft 69. A star wheel 70 is secured to the shaft 12 and a crank-arm 71, which is secured to the shaft 69, extends into the path of movement of the arms 72 on the star wheel 70 so that the kicker 68 will be moved to such an angular position that its lower end will be to the rear of the guide 43 and behind the pins 23 on the covers 20. A weight 73 is hung from a crank-arm 74, which is also secured to the shaft 69, and rocks the shaft 69, when the crank-arm 71 is disengaged by an arm 72, to throw the kicker 68 outwardly against a pin 23 and open a cover 20. A stop 75 limits the downward movement of the weight 73, leaving the crank-arm 71 in a position to be rocked by the next succeeding arm 72 of the star wheel 70. It will be understood, of course, that the timing of the mechanism is such that an arm 72 of the star wheel 70 moves the kicker 68 back in time for it to be in a position to act upon the pin 23 of each cover 20.

When the bottles are discharged by gravity from the compartments 19 of the bottle receptacles 18, they slide down inclines 76 and are checked by springs 77 and are stopped by snubbers 78 which are attached to a shaft 79, provided with a crank 80. A crank-arm 81 is pivoted to the soaking tank 1 and extends into the path of movement of the arms 72 of the star wheel 70, and a link 82 connects the crank-arm 81 with the crank 80 so that the star wheel 70 will move the snubbers 78 into the paths of movement of bottles and, when an arm 72 is disengaged from the crank-arm 81, the crank-arm 81 can fall and permit the shaft 79 to rock and raise the snubbers 78 to release the bottles. The bottles are then fed positively, by an endless conveyor 83 under a rotatable scrubbing brush 84 and delivered to bottle holders 85 of an endless conveyor 86 which conveys the bottles over the washing head 87 in the man-

ner to be presently described. Each bottle is retained between guides 88 and is supported by two inclined rollers 89 as it is fed by the endless conveyor 83 beneath the scrubbing brush 84, and the rollers 89 are all rotated in the same direction by a sprocket chain 90 which engages with sprocket wheels 91, one of which is secured to each roller 89. It will be noticed from an examination of Fig. 3 of the drawings that the sprocket chain 90 is driven by the sprocket wheel 92 on the shaft 93 and runs loose on its lower run while engaging with the sprocket wheels 91 on its upper run. A pipe 94 sprays water over the exteriors of the bottles as they reach the brush 84, and the bottles are rotated about their axes by the rotation of the two rollers which support each bottle. The guides 88 provide pathways for the bottles and these pathways correspond in number 85 with the number of compartments 19 in a bottle receptacle 18, and each guide 88 is located substantially over the axis of a roller 89 so that each bottle will be supported by two rollers.

The shaft 27 is provided with a sprocket wheel 95 which drives the shaft 96 by means of a sprocket chain 97 and a sprocket wheel 98.

The endless conveyor 83 is composed, in part, of sprocket chains 99 and 100 which run on sprocket wheels 101, 102, 103 and 104, which are secured in pairs to shafts 105 and 106. The shaft 106 is driven by the shaft 96 by means of the sprocket wheel 107, 100 sprocket chain 108, sprocket wheel 109, shaft 110, worm 111, and worm wheel 112 which is secured to the shaft 106. A bevel gear 113 on the shaft 96 drives the bevel gear 114 on the shaft 115, and the scrubbing brush 84 is driven from the shaft 115 by the sprocket wheel 116, sprocket chain 117, and sprocket wheel 118, while the rollers 89 are driven from the same shaft 115 by the sprocket wheel 119, sprocket chain 120, 110 sprocket wheel 121, shaft 122, bevel gear 123, bevel gear 124, and shaft 93 to which the sprocket wheel 92 is secured.

The shaft 96 is provided with a worm 126 which drives a worm wheel 127 on the shaft 128. The shaft 128 is provided with a valve operating cam 129, a washing head cam 130, and a one-toothed driving gear 131 which forms a part of an intermittent gear mechanism. The endless conveyor 86 is composed of sprocket chains 132 and 133 to which the bottle holders 85 are connected and the sprocket chains 132 and 133 pass around sprocket wheels 134, 135, 136, 137, 138 and 139 which are secured in pairs to shafts 140, 125 141 and 142. The shaft 140 has secured to it the four-slotted gear 143 which is driven by the one-toothed driving gear 131, thus completing the intermittent gear mechanism by which the endless conveyor 86 is driven 130

by a step-by-step motion, giving alternate periods of motion and rest or stop. The bottle holders 85 are each provided with a plurality of apertures 144 to receive bottles with their necks down, and with the necks of the bottles projecting below the bottle holders a sufficient distance for the proper operation of the washing head 87.

The washing head 87 is provided with two rows, 145 and 146, of washers 147, the two rows being spaced apart a distance equal to a step of the movement of the endless conveyor 86. The washing head 87 is movable vertically and is rigidly secured to rods 148 and 149 which are guided by guides 150 and 151. The washing head cam 130 rocks a shaft 152 by a crank-arm 153, provided with an anti-friction roller 154, and crank-arms 155 and 156 extend under the rods 148 and 149. The washing head 87 descends by gravity and is elevated by the washing head cam 130, but both the descending and the elevating movements are controlled by the cam 130 because the weight of the washing head keeps the antifriction roller 154 constantly in contact with the cam 130. The washing head 87 is provided with a water chamber 157 and an air chamber 158, and each washer 147 is provided with a nozzle 159 which communicates with the water chamber 157 and a concentric nozzle 160 which communicates with the air chamber 158. Each washer 147 is provided with a cup 161 to receive the neck of a bottle and substantially center the neck of a bottle with respect to the nozzle 159, and orifices 162 and 163 are provided for the escape of water and air. Water under pressure is supplied to the water chamber 157 from any suitable source of supply through the pipe 164, valve 165 and the flexible connection 166, and compressed air is supplied to the air chamber 158 from any suitable source of supply through the pipe 167, valve 168 and the flexible connection 169. The water valve 165 and the air valve 168 are similar in construction and are illustrated by Figs. 8 and 9 of the drawings. The valve members 170 are of the poppet type and close with the pressures. Rock shafts 171 are provided with projections 172 which underlie the valve stems 173 to lift the valve members 170 to open the valves. The valve levers 174 and 175 are secured to the respective rock shafts 171 and are connected by a turnbuckle link 176 for adjusting the angular relation of the valve levers so that the water can be turned on prior to the air and be shut off subsequent to the air. Both valves 165 and 168 are opened and closed by a cam 129 which rotates between arms 178 and 179 of a bell-crank lever 180 which is connected by a link 181 with an extension of the valve lever 175. When bottles 125 are approaching the discharging point from the endless conveyor

86, they are prevented from falling out of the bottle holders 85 by a shield 177, but, as they pass beyond the shield 177, they can slide out of the bottle receptacles or bottle holders 85 onto movable receivers 182 which are normally inclined as continuations of fixed inclined receivers 183. The extent of movement of the bottles under the influence of gravity is limited by the inclined ends of the bottle supports 183'. The bottles are righted and moved onto and along the bottle supports 183' by pairs of fingers 184 which are secured to a rock shaft 185. The rock shaft 185 is rocked in timed relation with the step-by-step movement of the endless conveyor 86 by cranks 186 and connecting rods 187 which may be connected with cranks 188 on the shaft 152. The drawings illustrate a table 189 to receive the bottles from the bottle supports 183.

The movable receivers 182 are connected to a rock shaft 190 which is held in a predetermined position by a weight 191, a stop, not shown, determining the extent of downward movement of the weight. The rock shaft 190 is also provided with a valve operating arm 192 which swings so as to move the valve handle 193 of the air valve 37 to shut off the supply of compressed air to the cylinder 32 and to permit the compressed air to exhaust from the cylinder 32 so that the spring 33 will disengage the clutch members 29 and 30 and stop the movements of the movable parts of the apparatus. A bottle, or something other than a bottle, which had passed the apparatus up to the final discharge point might not free itself from a bottle holder and would rock the rock shaft 190 and stop the operation of the apparatus without causing damage. The valve 38 provides for manual control of the apparatus and is illustrated by the drawings as placed at a convenient location with respect to the table 189 so that the delivery of washed bottles can be controlled, if desirable. The valves 36 and 37 can also be controlled or operated manually if desired in addition to their automatic operations, and the movable parts of the apparatus cannot be set in motion until all three valves 36, 37 and 38 are properly set for operation. Such a construction insures the safety of the apparatus and its operators.

The reference numeral 194 designates a hood or reflector covering electric lights to strongly illuminate the bottles so that the inspectors can carefully examine them for imperfections after they are cleaned.

The brush 84 is supported by the shaft 195, to which it is secured by arms, and the shaft 195 can be turned to properly set the brush, as it wears for example, and is retained in the desired position by the bolt 196.

The operation of the apparatus will be perfectly clear from the foregoing detailed

description of its construction and operation.

What is claimed is:

1. The combination in bottle cleaning apparatus, of a conveyor, including bottle receptacles provided with covers, power mechanism for operating the conveyor, a fluid-pressure motor for controlling the operation of the conveyor, yieldable means for closing 10 said covers, and means controlled by said yieldable means to stop the operation of the conveyor.
2. The combination in bottle cleaning apparatus, of a conveyor, including bottle receptacles provided with covers, power mechanism for operating the conveyor, a fluid-pressure motor for controlling the operation of the conveyor, cams for closing said covers, and a valve controlled by said cams for controlling said fluid-pressure motor.
3. The combination in bottle cleaning apparatus, of a conveyor for bottles, power mechanism for operating the conveyor, a fluid-pressure motor for controlling the operation 25 of the conveyor, movable receivers for the bottles, and means for controlling said fluid-pressure motor by a movement of the said movable receivers.
4. The combination in bottle cleaning apparatus, of conveyors, one of said conveyors including bottle receptacles provided with covers, power mechanism for operating the conveyors, a fluid-pressure motor for controlling the operation of the conveyors, movable 35 bottle receivers, means for controlling the said fluid-pressure motor by the covers of the bottle receptacles, and means for controlling said fluid-pressure motor by said movable bottle receivers.
5. The combination in bottle cleaning apparatus, of conveyors, one of said conveyors including bottle receptacles provided with covers, movable bottle receivers, a fluid-pressure motor for controlling the operation of 45 said conveyors, and a plurality of valves for controlling said fluid-pressure motor, one of said valves being adapted to be automatically operated by the movement of one of said conveyors.
6. The combination with a bottle cleaning apparatus having a conveyor and bottle receptacles carried thereby, said receptacles being provided with covers adapted to hold the bottles in proper position therein, of 55 means adapted and arranged for cooperation with each of said covers to control the operation of said conveyor when said cover fails to assume a predetermined position with respect to said means.
7. In a machine of the character described, a conveyor provided with bottle receptacles having bottle-retaining covers, driving means for said conveyor, means for connecting and disconnecting said conveyor to and from said 65 driving means, actuating means for said last-mentioned means, and means adapted and arranged for engagement with said covers to cause the latter to close and to cause said actuating means to function when said covers are prevented from closing.
8. In a machine of the character described, a conveyor provided with bottle receptacles having bottle-retaining covers, driving means for said conveyor, means for connecting and disconnecting said conveyor to and from said 70 driving means, actuating means for said last-mentioned means, and a cam adapted and arranged for engagement with said covers to cause the latter to close and to cause said actuating means to function when said covers are prevented from closing.
9. The combination with bottle cleaning apparatus including a conveyor for bottles, power mechanism for operating the conveyor, means for controlling the operation of the 75 conveyor, and bottle receivers carried by said conveyor for movement therewith, of means engageable with said receivers upon movement thereof and operable upon such engagement to actuate said controlling means.
10. A bottle cleaning apparatus comprising a conveyor having bottle receptacles, means cooperatively disposed with respect to said bottle receptacles and occupying a predetermined position when unbroken bottles 80 of proper size are placed in the receptacles and adapted to occupy a different position when bottles of improper size and broken bottles which have displacing engagement therewith are placed in the receptacles, a clutch controlled drive for the conveyor, a fluid pressure motor controlling the clutch and a valve controlled by said means and regulating the supply and exhaust of fluid pressure to the fluid pressure motor.
11. A bottle cleaning apparatus comprising a conveyor having bottle receptacles, automatic stop control means cooperatively disposed with respect to said bottle receptacles and automatically movable to a stopping position when a bottle, liable to cause damage to the machine, is in a bottle receptacle, a clutch controlled drive for the conveyor, a fluid pressure motor controlling the clutch, a valve controlling the supply and exhaust of 90 the fluid pressure to the fluid pressure motor and operating mechanism for the valve subject to the control of said automatic stop control means.
12. A bottle cleaning apparatus comprising a conveyor having bottle receptacles, a second conveyor provided with bottle receivers, a clutch controlled drive common to said conveyors, a fluid pressure motor controlling the clutch, a plurality of valves each of which controls the supply and exhaust of fluid pressure to said motor, a plurality of automatic stop control means cooperatively disposed with respect to said bottle receptacles and said bottle receivers respectively, and auto- 100

matically movable to stopping position when a bottle, liable to cause damage, is in the bottle receptacle or the bottle receivers, and operating mechanisms for the valves controlled by said automatic stop control means.

13. A bottle cleaning apparatus comprising a plurality of conveyors having means for handling the bottles to be cleaned, a clutch controlled drive common to the several conveyors, a fluid pressure motor controlling the clutch of said drive, a plurality of valves located at different distances from the fluid pressure motor, each valve being adapted to independently control the supply and exhaust of fluid pressure to said motor, and automatic stop control means regulating the action of the valves and cooperatively disposed with respect to the conveyors and their means for handling the bottles, and adapted to be automatically moved to stopping position when a bottle, liable to cause damage to the machine, is handled by the means of the conveyor.

In witness whereof I hereto affix my signature.
